Patented Jan. 17, 1922.

3 SHEETS—SHEET 3.

UNITED STATES PATENT OFFICE.

FRED WALKER, OF RHODES, IOWA.

AUTOMATIC DOOR-OPERATING MECHANISM.

1,403,927.

Specification of Letters Patent. Patented Jan. 17, 1922.

Application filed February 5, 1921. Serial No. 442,709.

To all whom it may concern:

Be it known that I, FRED WALKER, a citizen of the United States, residing at Rhodes, in the county of Marshall and State 5 of Iowa, have invented certain new and useful Improvements in Automatic Door-Operating Mechanism, of which the following is a specification.

This invention relates to improvements in 10 automatic door operating mechanisms, and more particularly to door operating mechanisms for garages and the like.

An object of the invention is to provide a suitable automatic door operating mechanism 15 which will positively open the door of a garage, when the automobile rolls upon the outer platform or track, and which will close immediately as the automobile is within the garage.

20 A further object is to provide means for manually operating the doors, thereby not necessitating the actual entrance of an automobile whenever the doors are to be opened.

25 Another object is to provide suitable means for locking the doors in closed position, either from the inside or outside of the garage.

Other objects will appear as the description proceeds.

In the accompanying drawings, which constitute a part of my application—

Figure 1 is a front elevation of the garage doors, and operating mechanism;

35 Figure 2 is a side elevation of the garage and platforms;

Figure 3 is a vertical longitudinal section of the platforms and operating mechanism;

40 Figure 4 is a sectional view taken on the lines 4—4 of Figure 3;

Figure 5 is a sectional view taken on the line 5—5 of Figure 1;

Figure 6 is a sectional view taken on the 45 line 6—6 of Figure 2;

Figure 7 is a detail view of the joint between the platforms;

Figure 8 is a detail view of the door operating gearing, and

50 Figure 9 is a detail view of the bracket carrying the main door operating gear.

Like characters of reference are used throughout the following specification to designate corresponding parts.

55 The frame or walls of the garage 1 are

provided at their forward end with the folding slide doors 2, which may or may not operate in the channel bar or slot 3 at the top of said doors and are provided with the connecting bars 3' at their upper edges. 60 These doors are hinged at their central portions, and are attached rigidly at their opposite ends to the vertical pivoted rods 4, located at either side of the entrance of the garage. These doors 2 are of usual construction, and may be provided with glass windows 5 in their upper portions if desired.

A pivoted platform or track 6, is hinged at either side, at its outer end to the base 70 boards or frame 7, as at 8. Likewise a second platform 9 or track extends from the inner end of the frame 7, and is correspondingly hinged at its inner end as at 10. Bearings or rollers 11 are carried by 75 the platform 6, where it connects with the platform 9, and are slidably movable in the slots 12 at the end of the platform 9.

Guide posts or fingers 13 are attached at 80 opposite sides of the frame 7, and extend through the slots 14 in the platform 6. Positioned about these fingers 13, are the coil springs 14, which tend to normally keep the platforms 6 and 9 in raised position.

Attached to either side of the garage walls 85 1, are the brackets or mountings 15, which serve as bearings for the pivoted rods 4. These brackets 15, also carry the stub shafts 16, on which are rotatably mounted the large gear wheels 17, which are in turn connected together by means of the crank shaft 18. Attached to the lower ends of the rods 4, and in mesh with the gear wheels 17, are the gear segments 19.

A transverse rod 20 is mounted between 95 the side members of the frame 7, and carries at one of its ends the small pinion or gear wheel 21, which in turn meshes with a larger gear wheel 22, mounted on said frame 7. The handle 23 is attached to the gear 22, for rotating the same, which causes the rod 20 to rotate, thereby winding in on the chains 24 attached to the lower surface of the platform 9, to pull the same down, and thereby open the garage doors. A 100 dog 25 is adapted to engage the gear 21, to hold the same in locked position. Thus it will be seen that the doors may be opened manually.

A U-shape member 26 is mounted trans- 110

versely across and between the frame 7, and is provided at one of its ends with the handle portion 27. This member 26 is used to lock the platforms in raised position, and is held 5 in locked position by means of the latch 28, adjacent the said handle member 27.

From the foregoing description, it will be seen that the operation of the mechanism is as follows: The springs 14 normally tend 10 to hold the doors closed and the platforms 6 and 9 in raised position. When an automobile runs upon the platform 6, it starts to sink downward, thereby causing the large gear wheels 17 to rotate, due to the fact that 15 the platform 6 then seats on and presses the crank shaft 18 downward. The rotation of the gear wheels 17 cause the segment gears 19 to rotate, thereby sliding and folding the doors back in open position. As soon as the 20 automobile has entered the garage, and is off of the platform 9, the springs 14, automatically raise the platforms and close the doors. As before mentioned the doors can be manually opened and locked, or locked 25 in closed position.

The end closures 29 are used to close the space at the ends of the platform 6, to prevent anything from getting thereunder.

While I have specifically described my invention, I do not intend to limit myself to this 30 specific form, as many minor changes in detail of construction may be resorted to without departing from the spirit of the invention.

Having thus described my invention what I claim as new and desire to secure by Letters Patent of the United States is:—

1. The combination of a plurality of 40 swinging doors, bracket members adjacent the lower portions of said doors, rods mounted in said bracket members, gear segments on said rods, gears rotatably mounted on said brackets and meshing with said gear segments, a pair of adjustably interconnected platforms, and independent means for man-

ually moving the platforms to actuate the doors.

2. A door operating mechanism comprising a plurality of swinging doors, a pair of 50 adjustable interconnected platforms, gearing mounted at the opposite sides of said platforms, a crank connecting said gearing above the axis of said gears for cooperating with said platforms, whereby the doors will 55 be positively opened when weight is applied to the platforms.

3. A door operating mechanism comprising a plurality of swinging doors, a hinged platform, gearing for automatically opening 60 said doors when weight is applied to said platform, a shaft extending transverse of and under said platform, means connecting said platform with said shaft, and manually operated means for rotating said shaft 65 whereby the platform will be lowered and the doors opened.

4. A door operating mechanism comprising a plurality of swinging doors, a hinged platform, gearing at the opposite sides of 70 said platform, a crank connecting said gearing above the axis of said gears for cooperating with said platform for automatically opening said doors, guide posts extending through said platform, and resilient means 75 surrounding said posts for automatically raising said platform and closing said doors.

5. The combination with a swinging door, of bracket members adjacent the lower portion of said door, a rod rotatably mounted 80 in each of said brackets, said door being fixed to said rods, a gear mounted on each of said brackets, gear segments carried by each of said rods and meshing with said gears, a plurality of interconnected platforms, a 85 crank connecting said gears above the axis of the gears and cooperating with said platform for automatically opening the door when weight is applied to the platform.

In testimony whereof I affix my signature. 90

FRED WALKER.
